Application August 9, 1945, Serial No. 609,740

18 Claims. (Cl. 273—102.1)

1

This invention relates to dart boards, gun and pistol targets, archery targets, and similar targets for other missiles; the invention relates generally to concentric targets having a central circular target of highest point value surrounded by a plurality of annular targets concentrically disposed and of graduated point values decreasing in value from the central target or "bull's-eye" to the outer annular target, which has the lowest point value.

The principal object of the invention is to provide a concentric target board of the class described which will automatically totalize the point values of the individual target areas that are hit by the missiles. Accordingly, the improved target board will immediately add the point value of the particular target area hit to the aggregated point values of previous hits, so that the improved board indicates, for example, at a window provided for that purpose, the total score of point value of hits made. Another object of the invention is to provide a target device which, in addition to totalizing the point values of hits made, will visually and momentarily indicate the particular target area that is hit; that is, besides adding the point value of the particular target area hit (so that the grand total will be indicated), the device will also show the particular target area hit by either momentarily indicating the point value thereof or by other visual indications, as will be more fully described herein.

The automatic totalizing and indicating target device of this invention may be used with any type of missile, and especially for darts (thrown by hand or by a dart propelling instrument) and for pellets fired from air pistols or rifles (or for bullets fired from cartridge-loaded pistols or guns). When concentric targets are used for pellets (which term will be understood to include bullets), it is difficult to ascertain, from the distance of the aimed air rifle (which term will be understood to include air pistols, cartridge-loaded pistols, guns, etc.), which target area had been hit by the pellet. In using the improved target device of this invention, it can be readily ascertained, from the distance of the aimed air rifle, which target area had been hit by the pellet; the improved target device visually and momentarily indicates the target area hit by the pellet in a manner so that the indication can be readily seen from a distance.

When concentric targets are used for darts, it usually can be seen from a distance, which target area had been hit, by reason of the dart remaining stuck in the target. Frequently, how-

2

ever, the dart drops off the board, either because of imperfection in the board surface or in the piercing point of the dart; in such cases, the player loses the point value of the target area that had been hit. The improved target device of this invention avoids this possibility, because the point value of the target area hit will have been added to the grand total.

In one form of the improved dart target of this invention, the target areas are made of suitable penetrable material so that the darts will remain in hit positions; this form of dart target device need have only the feature of totalizing the point values and need not have the feature of momentarily indicating each target area hit, since the darts themselves will show this. In another form of the improved dart device, the target areas are made of impervious material so that the darts do not remain in hit positions; this form would have both the totalizing feature and the feature of visually indicating the target area when hit. Still another object of this invention is to provide a target for darts, which will show the total point values of the target areas hit and momentarily indicate each target area that is hit, and which will not use sharply pointed darts. The usual dart has a rather sharp point which, when thrown even from short distances, is capable of inflicting injury to person or property, and is, therefore, dangerous, especially when handled by children or careless persons. The form of the improved dart target in which the target areas are made of impervious material, mentioned above, uses blunt-ended darts which may be used without fear of injury. Another advantage of this form of improved dart target is that previously thrown darts do not remain on the board to hinder subsequently thrown darts; it frequently happens in using the common dart board and sharply pointed darts, that a dart will hit another dart that is stuck on the board and will be prevented from scoring a hit, and will often cause the stuck dart to fall off the board, thus causing the player to lose the point values of two hits. Also, they mar the target surface, and soon make portions incapable of retaining the darts.

Another object of the invention is to provide means for catching the thrown darts after they had scored hits, the point values of which had been added to the previous total. This provision is especially convenient in the form of the improved device having impervious target areas, but may also be used in the form of improved device in which the target areas are made of

penetrable material, since sharp-pointed darts quite frequently fall off the board, as pointed out above. Another object of the invention is to provide the improved target device as described with a receptacle hinged thereto which encloses the target device to present a closed box for ease in handling and storing (and in which the darts, or air pistol, etc. may be kept) and which when in opened position serves as a receptacle to catch the darts rebounding from the target.

Another object of the invention is to provide an improved target device as described which will be of compact size so that it can be readily hung on the wall or other suitable surface; such device may or may not be implemented with the dual-purpose receptacle mentioned above. It is sometimes difficult, especially in smaller apartments, to find a suitable wall upon which to hang a dart board or air rifle target. Still another object of this invention is to provide an improved target device as described having the dual-purpose receptacle, described above, which, when in open position, may be secured to a tripod or similar support and which will hold the target in rigid vertical position.

For the attainment of these and such other objects of invention as may appear or be pointed out herein, embodiments of the invention are shown in the accompanying drawings, wherein:

Fig. 1 is a front view of the improved device implemented with the dual-purpose receptacle, mentioned above, in open position and secured to a tripod;

Fig. 2 is a side view of the improved device of Fig. 1 with the dual-purpose receptacle in closed position for storing the device;

Fig. 3 is a front view of the improved device of circular form, having the totalizing feature but no separate indicators for the individual target areas, the hitting of the respective target areas being momentarily indicated by other means, as will be described;

Fig. 4 is an elevational sectional view through the improved device;

Fig. 5 is a front view of the device of Fig. 4, but on a smaller scale, with the front plate mostly broken away;

Fig. 6 is a sectional view of the lower portion of Fig. 4, showing a detail of the securing of the front plate;

Fig. 7 is a sectional view of the lower portion of Fig. 4, showing the use of a rectangular housing for the circular target areas and circular front plate;

Fig. 8 is a sectional view of the lower portion of Fig. 4, showing the by-pass dog for holding the indicating slide;

Fig. 9 is a front view of a modified form of the invention; and

Fig. 10 is a fragmentary, sectional view of a preferred form.

The improved device has a central circular disc area and a number of annular disc areas concentrically disposed relative thereto. There may be any desired number of annular target areas; four annular target areas are shown in Figs. 1 and 3 and two annular target areas are shown in Figs. 4 and 5. The central disc target is designated 10 in Figs. 4 and 5 and is stamped from sheet metal to present two arcuate portions 11 rearwardly extending from an annular flange 12. To the annular flange 12 is secured a circular disc 13, which may be formed of metal or other suitable material. The arcuate portions 11 are received in arcuate slots 2, see Fig. 5, formed in

front plate 1. As clearly seen in Fig. 5, arcuate slots 2 are longer than arcuate portions 11, so that the central disc target 10 may turn between the limits of the arcuate slots (for a purpose subsequently described). Arcuate portions 11 of the central disc target are slidably supported on arcuate bearing flanges 3 extending rearwardly, Fig. 4, from front plate 1 and which, see Fig. 5, extend the length of arcuate slots 2. The arcuate slots 2 and arcuate bearing flanges 3 may be formed from the front plate by slitting and stamping.

The inner annular target 20 has similar arcuate portions 21 extending rearwardly from an annular flange 22 to which is secured an annular target strip 23. It will be noted that inner annular target 20 has four arcuate portions 21, whereas the central disc target 10 has only two. The arcuate portions 21 are received in arcuate slots 4 of front frame 1 for an extent of turning movement as limited by the ends of slots 4, and are slidably supported on arcuate bearing flanges 5 stamped from the front plate. Similarly, the outer annular target 30 has four arcuate portions 31 extending rearwardly from an annular flange 32 supporting an annular target strip 33, the arcuate portions 31 being received in arcuate slots 6 and slidably supported on arcuate bearing flanges 7 slotted and stamped from the front plate 1. As clearly shown in Fig. 4, front plate 1 is dished at 8 to form a recess in which the front portions of the target members 10, 20, and 30 are received, and a peripheral flange 9 which is flush with the front surfaces, 13, 23, 33 of the target members. The target flanges may be held between both lower (shown) and upper flanges (not shown).

Spaced from the peripheral edge of the peripheral flange 9, Fig. 4, to provide a narrow annular slot 17, and aligned with peripheral flange 9 to present a flush front surface, is the annular front flange 49 of a rear plate 40, which is stamped from sheet metal to form a housing as clearly seen in Fig. 4. Within the housing and behind the marginal portions of peripheral flange 9 and the annular front flange 49 of the housing, is slidably supported an annular totalizing slide 50. Totalizing slide 50 is stamped from sheet metal to form the annular slide 50 and a rearwardly extending cylindrical portion 51, see Fig. 4. The cylindrical portion 41 of the housing serves as an outer bearing surface for cylindrical portion 51 of the totalizing member 50. The juncture 43 between the front flange 49 and cylindrical portion 41 of the housing provides an annular bearing surface for the folded edge 58 between totalizing slide 50 and cylindrical portion 51.

Annular totalizing slide 50 is provided with a knob 59 at the front of the device having a reduced portion 57 which clears through the aforementioned annular slot 17, the purpose of which is to re-set the totalizing slide to zero and to tension the trigger mechanism which will be subsequently described. While the outer edge (lower, in Fig. 4) 58 of totalizing member 50 is slidably supported in the annular bend 43 of the housing, the inner edge (upper, in Fig. 4) is slidably supported in a brace member 29, and more particularly, in an arcuate recess 28 between brace member 29 and peripheral flange 9 of the front plate. Brace member 29 is secured to peripheral flange 9, as by spot welding, while the rear portion 29^X of the brace member is secured to a cylindrical stepped portion 46 of the housing, Fig. 6. Brace member 29 does not extend

completely around the housing but is provided at spaced points around the housing, as clearly seen in Fig. 5, the reason for which will be soon apparent. Front plate 1 is also supported at its central portion by a cylindrical spool 40^x, Fig. 4, the rear wall of which is secured to rear plate 40 of the housing, its cylindrical surface fitting within the arcuate flanges 3 of the front plate 1 to which the spool is secured in any suitable manner. In a simple form of the improved device, front plate 1 may be similarly secured to rear wall 40 by a spool 40^x, and the peripheral flange 9 of the front plate steadied by the annular totalizing slide 50 itself, the upper (or inner) edge of which may be guided in a simple annular flange secured to the inside of peripheral flange 9, see Fig. 10.

Annular totalizing slide 50, Fig. 5, bears numerals 52 in an arithmetic series starting from a number representing the point value of the outermost annular target member. In the example shown in Fig. 5, it is assumed that the outer annular target member 30 has a point value of "20"; hence the first member of the series on the totalizing slide 50 is "20." The parts are shown in Fig. 5 ready for the first dart, pellet or other missile; in this position of totalizing slide 50, its first number "20" is just to the right (counter-clockwise) of a window 9^x provided in the peripheral flange 9 of the front plate and in front flange 49 of the housing. The totalizing slide 50 is turned, by means soon to be described, in a clockwise direction when the target areas are hit for an extent depending upon the particular target area hit. For example, if the outer target member 30 is hit, totalizing slide 50 is moved one step clockwise to bring the first number "20" at window 9^x to indicate the point value of that target member. The numerals increase arithmetically in a counterclockwise direction in units of "20," so that the succeeding numbers are "40," "60," etc. If outer target member 30 is hit a second time, totalizing slide 50 will be turned clockwise another step bringing into view number "40" which thus represents the summation of the point value of hits made. The inner annular target 20 is assumed to have a point value of "60" so that, when 20 is hit, totalizing slide 50 will be turned three steps to bring—assuming there were no previous hits—"60" to view at window 9^x. If the first hit had been "20," the three-step clockwise turning of totalizing slide 50 when inner annular target 20 is hit, will cause number "80" to appear, representing the total of all hits made. Assuming that the central disc target 10 represents a point value of "100," the hitting of target 10 will cause a five-step turning of totalizing slide 50. The numbers increase, in the manner explained, counter-clockwise up to a number representing the highest score of point values for the particular device for a given number of aimed missiles.

Totalizing slide 50 is urged to turn in a clockwise direction by a helical spring 53, Fig. 5, one end of which is secured to the cylindrical portion 51 of the totalizing slide. Helical spring 53 extends annularly about the totalizing slide and is disposed behind annular slide 50, see Figs. 4, 6, 7 and 8; in Figs. 4 and 6, helical spring 53 is disposed inwardly of (above) the cylindrical portion 51, while in Figs. 7 and 8, it is disposed outwardly of (below) cylindrical portion 51. In either case, an annular passage is provided for confining helical spring 53. In Figs. 4 and 6, 75 4 and 8) position. In the normal, forward posi-

the annular passage is defined by the upper portion of totalizing slide 50, the upper surface of cylindrical portion 51, and an annular ring 27 of brace member 29; the fourth side of the annular passage is defined by a flange 27^x, Fig. 6, tongued out of the brace member. In Figs. 7 and 8, the annular passage for helical spring 53 is defined by the lower portion of totalizing slide 50 and the underside of cylindrical portion 51; in Fig. 10, 7, the other two sides of the annular passage are defined by an annular curved portion 67 of an annular rim member 69 (which will be more fully described subsequently); in Fig. 8, the other two sides of the annular passage are defined by an annular curved portion 47 of the housing.

While one end of helical spring 53 is secured to cylindrical portion 51 of totalizing slide 50, see Fig. 5, the other end, substantially 360° counter-clockwise therefrom, is secured to either 20 wall 27 of the annular spring passage, Fig. 4, or to wall 67, Fig. 7, or to wall 47, Fig. 8, of the annular passage. For facility in illustration, Figs. 4-8 show an annular passage capable of 25 housing a helical spring extending, in stretched condition, only once about the cylindrical portion 51; this construction may be used where the annular indicating slide is not required to make a complete revolution. Where a full 360° turning of the slide is desired, the helical spring 30 53 would be housed in a spiral passage 93, Fig. 10, disposed between shoulder 8 of the front plate and cylindrical portion 51 of the annular slide. The spiral coil spring would be secured to the 35 annular slide when the latter is turned 360° from its zero position, under some tension to give the totalizing slide the last step advance to its end position (in making a perfect score).

The cylindrical portion 51 of the totalizing slide has equi-spaced teeth 54 extending radially 40 inwardly thereof, and conveniently tabbed out of the cylindrical portion. Referring to Fig. 5, teeth 54 are spaced apart an angular degree equal to the angular spacing of the numerals 52, so that a one-tooth clockwise turning of the 45 totalizing slide will bring the succeeding numeral 52 to window 9^x. The spring 53 of the totalizing slide is tensioned by manually turning knob 59 in a counter-clockwise direction; knob 59 is shown in Fig. 5 in its position when spring 53 50 is fully tensioned and the first numeral 52 is just to the right (counter-clockwise) of window 9^x. The totalizing slide 50, tensioned for clockwise turning, is prevented from turning in this direction by a by-pass dog 74, Fig. 5, which is 55 pivotally mounted at 74a to a bracket member 72 secured to a flanged ring 70. As best seen in Fig. 4, flanged ring 70 is supported on the cylindrical rim 46 of the housing for a limited extent of axial sliding movement (to left and right, as viewed in Fig. 4) and is prevented from turning, as by one or more pins 43, Fig. 6, or tabs tongued up from rim 46 at spaced points around the ring member, which pins or tabs are 60 slidably received in axially oriented slots 73 provided in flanged ring 70. Bracket 72, which mounts by-pass dog 74 on the flanged ring 70, is U-shaped, as best seen in Fig. 8, with its rear leg secured to flange 71 of flanged ring 70 and with its front leg pivotally mounting by-pass dog 74 (at 74a). A spring, such as the coiled 65 spring 79, Fig. 4, is disposed between flange 71 of flanged ring 70 and rear wall 40 of the housing, which spring normally maintains the flanged ring in a forward (leftward, as shown in Figs. 70 4 and 8) position. In the normal, forward posi-

tion of flanged ring 70, the by-pass dog 74 is positioned in front of, i. e., clockwise, see Fig. 5, of a tooth 54 of the totalizing slide. A stop 75, which may be conveniently tabbed out of the mounting bracket 72, Fig. 5, prevents by-pass dog 74 from being turned, by tooth 54, to the left, see Fig. 5. Hence in the normal forward position of flanged ring 70, as shown in Fig. 8, by-pass dog 74 is positioned in front (clockwise) of a tooth 54 of the totalizing slide, as shown in Fig. 5, so that tooth 54, urged to turn clockwise by the tensioned spring 53, presses by-pass dog 74 leftwardly, in Fig. 5, against its stop 75. However, when the totalizing slide 50 is re-set to zero and its spring 53 re-tensioned, by manual counter-clockwise turning of knob 59, as already explained, by-pass dog 74 will not prevent counter-clockwise turning since the teeth 54 in moving counter-clockwise, as viewed in Fig. 5, will turn by-pass dog 74 to the right, away from its stop 75, a sufficient extent to enable the teeth to pass by. A small spring 76, Fig. 5, is provided to return the by-pass dog 74 to the left against its stop 75.

The flanged ring 70 is moved rearwardly to withdraw its by-pass dog 74 from in front of a tooth 54 of the totalizing slide 50, to permit the slide to turn clockwise each time one of the target members is hit. For this purpose, the target members are each provided with a pair of diametrically aligned radial arms. Referring to Fig. 5, the radial arms of the central disc target 10 are designated 15 and are secured by an arcuate base 14 to the arcuate portions 11 of central disc target 10; the radial arms 25 of the inner annular target 20 are secured by an arcuate base 24 to the arcuate portions 21 of annular target 20; the radial arms 35 of the outer target 30 are secured by an arcuate base 34 to the arcuate portions 31 of annular target 30. The distal ends of all the radial arms 15, 25, 35, are positioned at the teeth 54 of the totalizing slide, as clearly shown in Fig. 5. Only the radial arms 35 of the outer annular target 30 are shown in the side elevational view of Fig. 4. The description of the radial arms and their cooperation with totalizing slide 50 and flanged ring 70 will be confined to radial arms 35 shown in Fig. 4, it being understood that, so far as Fig. 4 is concerned, the other radial arms 25, 15 are constructed and operate in a similar manner. The construction and operation of both radial arms 35 are identical, so that it will be more convenient to confine attention to the lower arm 35 shown in Fig. 4. At its distal end, radial arm 35 is provided with a projection 37 which is in abutting relation to flange 71 of flanged ring 70, when the latter is in its normal forward position as shown in Fig. 4. When the outer annular target 30 is hit by a missile and moved inwardly, to the right, Fig. 4, by the impact thereof, the distal projection 37 of its radial arm 35 will shift flanged ring 70 rearwardly, to the right, to withdraw its by-pass dog 74 from blocking position relative to the teeth 54 of totalizing slide 50. Two radial arms 35 are provided so that flanged ring 70 will be contacted and pushed inwardly at two diametrically opposite points, to prevent possible tilting where only one radial arm is used; however, one radial arm 35 may be sufficient if the flanged ring 70 is mounted for easy axial shifting without tilting in its bearing surfaces. The spring 79 need not be a powerful one, but merely sufficiently strong to normally maintain flanged ring 70 in its forward position, which also, by

reason of the abutment between flange 71 of flanged ring 70 and distal projections 37 of radial arms 35 (and of radial arms of the other target members), normally maintains the target members in their forward positions, as shown in Fig. 4. In a preferred arrangement, Fig. 10, the arm 35 may extend straight radially, without the lateral extension terminating in projection 37; in this case, the forward edge of a plain axially mounted ring 90 abuts the radial arm 35 (and the other radial arms 25, 15, Fig. 5). Ring 90 has a number of spaced inward projections 91, which may be tongued out of the ring, pressed forwardly by the distal ends of a like number of spring strips 99, the other ends of which are secured to the rear wall of the housing.

Rearward movement of radial arm 35, in addition to withdrawing by-pass dog 74 to permit clockwise turning of totalizing slide 50, also limits such clockwise turning to extents depending upon the particular target hit. For this purpose, radial arm 35 has a distal projection 38, Fig. 4, which in the normal forward (left, in Fig. 4) position of the target member is to the left of a tooth 54 of the totalizing slide. As the radial arm 35 is moved rearwardly, to the right in Fig. 4, to withdraw by-pass dog 74 from in front of one tooth 54 of the totalizing slide, its projection 38 is positioned in front of another one of the teeth 54, the arrangement being such that the by-pass dog 74 is not fully withdrawn until distal projection 38 of the radial arm 35 is in proper position in front of a tooth 54. Withdrawal of by-pass dog 74 and interposing of distal projection 38 of radial arm 35 results in a clockwise turning of radial arm 35, together with the totalizing slide 50, and also of the outer annular target member 30 to which radial arm 35 is secured. It has already been described, with reference to Fig. 5, that the target members 10, 20, 30, have different degrees of turning, as limited by the length of the arcuate slots in front frame 1, respectively, 2, 4, 6, as compared with the lengths of their arcuate portions, respectively, 11, 21, 31, the degree of turning being largest (five teeth in the example shown) in the case of central disc target 10, and less (three teeth) in the case of the inner annular target 20, and least (one tooth) in the case of outer annular target 30.

Hence when the outer annular target 30 is hit and moved rearwardly by the impact, totalizing slide 50 together with radial arms 35 of target 30 will turn clockwise, as viewed in Fig. 5, the extent of which turning being limited to a one-tooth advance of slide 50 by reason of the fact that there is an angular difference equivalent to a one-tooth advance of the totalizing slide between arcuate portion 31 of outer annular target 30 and arcuate slot 6. But when inner annular target 20 is hit, the clockwise turning of totalizing slide 50 together with the radial arms 25 of that target will be for a three-tooth advance because there is an angular difference between arcuate portion 21 of inner annular target 20 and arcuate slot 4 equivalent to a three-tooth advance of totalizing slide. When central disc target 10 is hit, totalizing slide 50 together with radial arms 15 will make a clockwise advance of five teeth, in the example shown.

Rearward shifting of flanged ring 70, to the right in Fig. 4, will compress spring 79 which will tend to return the ring forwardly, to the left. To prevent this forward, leftward return of flanged ring until after the totalizing slide 50 had com-

pleted its clockwise turning to the extent depending upon the particular target area hit, there are provided at each radial arm 15, 25, 35, arcuate shields 42 of lengths (i. e., angular degrees), see Fig. 5, corresponding to the number of tooth-advance of the respective target members. For example, the pair of arcuate shields 42 associated with radial arms 15 of the central disc target 10, see Fig. 5, extend an angular distance equivalent to five teeth 54 of the totalizing slide 50, while the arcuate shields 42 associated with the radial arms 35 of the outer annual target 30 extend an angular distance equivalent to the spacing between teeth 54. It should be here pointed out that the target members 10, 20, 30 are normally maintained in a counter-clockwise position, i. e., with the counter-clockwise edges of their respective arcuate portions 11, 21, 31, abutting the counter-clockwise end of the slots in front plate 1, respectively, 2, 4, 6, as shown in Fig. 5; the target members are held in this normal counter-clockwise position by counter-weights, respectively, 16, 26, 36, Fig. 5, secured to their arcuate portions, respectively, 11, 21, 31. Conveniently, counter-weights 16, 26, 36 may be secured to the inside surface of the arcuate portions 11, 21, 31, in the space between the front plate 1 and the target surfaces 13, 23, 33, see Fig. 4. One end of the arcuate shields 42 is close to the distal end of radial arms 15, 25, 35 when in their said normal counter-clockwise position (as shown in Fig. 5) and extend in a clockwise direction therefrom. In the normal position of the parts, with the totalizing slide 50 held by by-pass dog 74 and with the radial arms 15, 25, 35 in their normal counter-clockwise position, the distal ends of the radial arms will be between a tooth 54 and the said initial end of its associated arcuate shield 42. When a particular target member is hit, the distal ends of the pair of radial arms secured to that target member will move rearwardly, clearing between teeth 54 of the totalizing slide and the said initial ends of the associated arcuate shields 42. Referring to Fig. 4, arcuate shields 42 are secured to the cylindrical portion 46 of the housing. The distal end of the radial arms, such as radial arm 35 shown in Fig. 4, is provided with a projection or lug 39 which, in the normal position of the parts (as shown in Fig. 4) is just to the left, or forward, of the arcuate shield 42.

When radial arm 35 is moved rearwardly, to the right in Fig. 4, upon hitting target member 30, its distal end clearing between tooth 54 of the totalizing slide and the initial end of its associated arcuate shield 42 (as described above with reference to Fig. 5), its distal lug 39 becomes positioned rearwardly of (to the right, Fig. 4) the arcuate shield 42. The by-pass dog 74 is not fully withdrawn from blocking engagement with the teeth of the totalizing slide until after lug 39 had been positioned to the rear (right, Fig. 4) of arcuate shield 42. Then when by-pass dog 74 is fully withdrawn, the tensioned spring 53 of the totalizing slide immediately turns slide 50 and its cylindrical portion 51, together with radial arm 35, in a clockwise direction, to position distal lug 39 behind arcuate shield 42. In this position, rearwardly or between arcuate shield 42 and the flanged ring 78, the distal lug 39 prevents flanged ring 78, under urgency of the compressed spring 79, from moving radial arm 35 forwardly (to the left, Fig. 4). As mentioned above, coiled spring 79 is not a powerful one, so that the tensioned spring 53 of the totalizing slide can turn radial arm 35 clockwise, despite the slight frictional re-

sistance due to the sliding engagement between lug 39 and the rear surface of the arcuate shield 42. Distal lug 39 thus maintains by-pass dog 74 in inoperative position withdrawn from the teeth 54 of the totalizing slide and maintains distal projection 38 of radial arm 35 in operative position in front of a tooth 54, for an angular degree of turning depending upon the length of the arcuate shield. As mentioned above, the arcuate lengths of shields 42 correspond to the extent of angular turning of the respective target members, so that the arcuate shields 42 terminate at angular positions corresponding to the angular position of the radial arms of the respective target members 10, 20, 30 when the latter reach the limit of their clockwise turning. That is, the arcuate shields 42 terminate at points such that the distal lug 39, Fig. 4, is no longer restrained by the shield 42 from being moved forwardly, to the left, by flanged ring 78, 20 when radial arm 35 and its target member 30 have reached the end of their assigned clockwise turning. When this point is reached, the flanged ring 78 urged by its compressed spring 79 forces the radial arm 35 to the left, to restore by-pass dog 74 in blocking position in front of a tooth 54 of the totalizing slide 50 and at the same time withdrawing distal projection 38 of the radial arm from the tooth 54 which had turned the radial arm clockwise. Forward, leftward, Fig. 4, movement of the radial arms returns the hit target member to normal forward position. In the forward position of the target member, the distal projection 38 of its radial arm being free of the teeth of the totalizing slide, the counter-weight 16, 26, 36, Fig. 5 of the target member will turn the target member in a counter-clockwise direction to return the member to its normal counter-clockwise position (as shown in Fig. 5). In the preferred construction, shown in Fig. 10, employing straight radial arms, arcuate shields 92 are secured on shoulder 8 of the front plate, cooperating with a lug or pin 94 on the lateral bend 35^x of radial arm 35.

To prevent a dart or other missile from being stuck between the edges of adjacent target members or to prevent it from striking both target members to falsely cause both members to add their point values to the total score, the target areas 13, 23, 33, Fig. 4, are separated by an annular clearance 18 which is wider than the thickness of the dart spindle; a similar wide clearance 18 is provided between the outer annular target 30 and peripheral flange 9 of the housing. A missile which just misses a target area to reach the annular clearance 18 separating that target area and the adjacent outer target area should be credited with the point value of the adjacent outer target. For this reason the annular targets 20 and 30 are provided with inwardly-turned annular flanges, respectively, 20^x, 30^x which overlap behind the outer marginal portions of the adjacent inner target area. For example, the inwardly-turned annular flange 30^x of the outer annular target member 30 overlaps behind the peripheral marginal portion of the inner annular target member 20. Hence if a dart or other missile passes in the annular clearance 18 separating target members 20 and 30, it will strike the annular overlapping flange 30^x of the outer target 30 causing that target member to be moved rearwardly to add its point value to the previous total as shown by totalizing slide 50.

In addition to the totalizing slide 50, there may be provided separate indicator slides for each target area to indicate which target area had been

hit. These, as clearly shown in Fig. 5, are short arcuate slides disposed beyond the outer annular target 30; the arcuate indicating slide associated with the central disc target area 10 is at the left and is designated 61, the arcuate indicating slide associated with the inner annular target area 20 is at the top and is designated 62, while the arcuate indicating slide associated with the outer annular target area 30 is at the right and is designated 63. Arcuate indicating slides 61, 62, 63 are slidably mounted behind peripheral flange 9 of the front plate, in arcuate guides 64. Arcuate indicator slide 63 associated with the outer annular target area 30 is shown in the lower part of Fig. 4 where it is seen to be slidably mounted between an arcuate recess 44 of brace member 29 and an arcuate guide formed by tonguing flange 64^x out of the front plate 1. Arcuate slides 61, 62, 63 bear numbers 65 corresponding to the point values of the respective target areas with which they are associated, which numbers 65 are visible in windows 19 in front peripheral flange 9 when the slides are turned in a clockwise direction, as viewed in Fig. 5.

Advantage is taken of the turning movements of the radial arms 15, 25, 35, described above in connection with the totalizing slide 50, for moving arcuate indicator slides 61, 62, 63, to display their respective numbers 65 at their window 19. Three different ways of doing this are shown in Fig. 5 in connection with the three arcuate indicator slides 61, 62, 63. In the case of indicator slide 63 associated with the outer annular target 30, a pin 66 projecting rearwardly from slide 63, see also Fig. 4, is received in an aperture 35^x provided in one of the radial arms 35, so that slide 63 partakes of the full turning movement of arm 35; when arm 35 is turned clockwise (by totalizing slide 50, as described above), arcuate indicator slide 63 is turned clockwise to display its number "20" at window 19 and is returned counter-clockwise when the arm 35 is returned in that direction (by counter-weight 36, as described above). In the case of arcuate indicator slide 61 associated with the central disc target 10, a rearwardly extending pin 68 is abutted by one of the radial arms 15 as it nears the end of its clockwise turning; continued turning of arm 15 causes a clockwise turning of arcuate indicator slide 61 to display its number "100" at window 19. As radial arm returns in counter-clockwise direction, arcuate slide 61 follows it, by force of gravity, until it is stopped by a suitable stop 64^x. In the case of arcuate indicator slide 62 associated with the inner annular target 20, two pins, 60, 60', project inwardly from slide 62 on either side of one of the radial arms 25. Pins 60, 60' are spaced apart so that, as radial arm 25 turns clockwise away from the pin 60, it will not abut the other pin 60' until near the end of its clockwise turning; continued clockwise turning of arm 25 in abutment with pin 60' causes a clockwise turning of arcuate slide 62 to display its number "60" at window 19. In the return counter-clockwise turning of arm 25, it moves away from pin 60' leaving indicator slide in shifted position (still displaying numeral 65), until arm 25 abuts the other pin 60 to return slide 62 in a counter-clockwise direction.

The individual indicator slides 61, 62, 63 may be omitted in certain types of the totalizing target device, for instance in models in which the target surfaces 13, 23, 33, see Fig. 4, are made of suitable penetrable material to enable the dart, of the sharply-pointed type, to remain in hit position. But even in this model, the individual indicators

may be added. The individual indicators would find their greatest utility in models of the totalizing target device designed to be used with blunted, safety darts or with air rifles and the like where it would otherwise be difficult or impossible to tell which target area had been hit.

In another form of the invention, shown in Fig. 3, it can be readily seen from a distance which target area had been hit without the use of individual indicator slides (61, 62, 63) as in Fig. 5. Five target areas are shown in Fig. 3; in addition to the central disc target area 10, the inner annular target area 20, and the outer annular target area 30, there are two intermediate annular target areas 20' and 30'. As in the model described more fully in connection with Fig. 5, the target areas of the model shown in Fig. 3 turn clockwise with the totalizing slide (to display the total score at window 9^x) and return in counter-clockwise direction. Also as in the case of the model of Fig. 5, the extent of this turning depends upon the respective target area, being largest in the case of the central disc target area 10 and smallest in the case of the outer annular target area 30. Advantage of this turning movement of the respective target areas may be taken to indicate, so that it can be readily seen from a distance, which target area had been hit. For this purpose, a distinctive horizontal line or band 55 and vertical line or band 56 are painted across the target areas. In the normal position, as shown in Fig. 3, the bands painted on the respective target areas will appear as a continuous horizontal and vertical line or cross. Suppose now that one of the target areas had been hit causing a clockwise turning of that target area; this will cause the four portions of the horizontal and vertical bands 55, 56 painted on the hit target area to be moved clockwise out of alignment with the bands of the other target areas which remain in alignment. This movement of the four bands of the hit target area out of alignment with the normal cross formation, seen in Fig. 3, will visually indicate which target area had been hit, so that this can be seen from the position of the player. It will be further noted that the central disc target 10 is turned the largest angular extent while the outer annular target 30 is turned the smallest angular extent. However, both will be seen from a distance because the bands of the outer annular target 30, while turning a limited angular degree, will be compensated by the fact that they are at a greater radial distance from the center, the actual visual movement of the bands depending upon both the angular degree of turning and the radial distance from the center.

The model shown in Fig. 3 is circular. The improved target device may also be square, and may be constructed in most respects similar to the device described above in connection with Figs. 4 and 5, except that instead of a circular or cylindrical housing (such as 40, 46, 41, 49, Fig. 4), the housing would be square or prismatic. A target device having a square housing is fragmentarily illustrated in Fig. 7. The square housing comprises a square rear wall 140 and four sides 141 extending forwardly from rear wall 140 to define a square box having relatively narrow sides as indicated by lower side 141, Fig. 7. At the front of the square housing and joining the forward edges of the said four sides 141 is a front flange or bordering frame 149. The outer edge of front flanges 149 is square; front flange 149 has a large circular opening which defines the

inner edge of the flanges. Within this large circular opening is received the circular peripheral flange 9 of front plate 1. The inner edge of front flange 9, i. e., at its said central circular opening, is spaced from the edge of peripheral flange 9 to leave an annular clearance or slot 17 for passage of the knob 38, Figs. 4, 5, as described above. Within the square housing 149—141—140, Fig. 7, is secured the annular rim 69 which had previously been described. The front annular flange 69a of annular rim 69 is secured to front flange 149 while its rear annular flange 69b is secured to rear plate 140 of the housing. Annular rim 69 is formed as shown in Fig. 7 to provide annular bearing surfaces for the annular totalizing slide 50 and its cylindrical portion 51 and for the flanged ring 79.

As pointed out in the statement of invention, the usual sharply pointed darts frequently fall or are thrown off the board, requiring such fallen darts to be gathered up from the floor. In using the improved target device described above as being especially designed for play with blunt, safety darts which are not intended to stick to the board, all the darts must be gathered up from the floor. To avoid this chore, the improved target device, Fig. 1, is provided with an open receptacle 77 in the form of an open box for catching the darts rebounding from the target. Receptacle 77 may be secured or attached to the lower edge of a square base 78 to which the round type of improved target (Fig. 3) is secured. Or the square type of improved target device, described above in connection with Fig. 7, may be used and the open receptacle 77 secured or attached thereto.

Receptacle 77 (for catching the darts rebounding or falling off the target areas) may also serve as an enclosing case for the device; this is shown in Figs. 1 and 2. Receptacle 77 is hinged, at 77a, to the lower corners of base 78 and turned to closed position, as shown in Fig. 2, to form a completely closed case enclosing the target device A, which may be conveniently handled and stored; in addition, the darts or air pistol or other instrument may be conveniently stored in the case. When in open position, as shown in Fig. 1, receptacle 77 serves to catch the darts rebounding or falling off the target areas.

The improved target device, whether the circular model of Fig. 3 or the square model described above in connection with Fig. 7 or the model of Fig. 1 having receptacle 77, may be hung from the wall or other suitable surface; for this purpose, the rear housing plate is provided with a pair of suitable apertures 80, see Figs. 3 and 1, for receiving the heads of a pair of nails, screws, or the like, projecting from the wall and spaced a proper distance apart. It is frequently inconvenient to hang the target on a wall or door. The model shown in Figs. 1 and 2 need not be hung from the wall, but may be conveniently supported on a suitable tripod. For this purpose the floor 81 of receptacle 77 is provided with an aperture 81a for a thumb screw 82, by which the receptacle 77 may be secured to the platform 83 of a tripod 84. The base 78 supporting the improved target device A is held in vertical position relative to receptacle 77 by a pair of hinged braces 85, the ends of which are secured to the base 78 and to the inside of the lateral sides of receptacle 77. As shown in Fig. 2, the aperture 81a in floor 81 of receptacle 77 is not at the center of the receptacle, but near to the side at which base plate 78 is hinged, so that the vertical line

from the center of gravity of the target A will fall well within the base of the tripod.

In the form of the invention thus far described with reference to Figs. 1-8, the arithmetic series of totalizing numbers are on annular slide 50 and only the number representing the total score appears at window 9x. Instead of this arrangement, the arithmetic series of totalizing numbers may be printed, painted, stenciled, pasted or otherwise impressed on the front face of the device, as is shown by annular numeral scale 86, Fig. 9, the numerals 87 increasing in arithmetic series clockwise from 12:00 o'clock position. A re-setting knob 38 is secured to the annular slide 50 (not shown in Fig. 9, but which may be similar—except for the absence of numerals—to annular totalizing slide 50 shown and described with reference to Figs. 1-8), the knob clearing in annular slot 17, as in Figs. 1-8. To knob 38 is secured a pointer 89 which moves in a circle around scale 86. The device is shown in zero position in Fig. 9. When a particular one of the target members, 10, 20, 20', 30, is hit, it causes—in the manner fully described in connection with Figs. 1-8—a clockwise turning of annular slide 50 and pointer 89 for an angular extent depending upon the point value of the target area hit, so that pointer 89 will be opposite the number (87) equal to the particular point value. When other target areas are hit the pointer is moved further clockwise, to a position opposite the number (87) representing the total score. Knob 38 is manually turned in a counter-clockwise direction to return pointer 89 to pristine or zero position (as shown in Fig. 9) and to tension the spring associated with annular slide 50.

One advantage of the form of the invention shown in Fig. 9 is that the angular position of the pointer 89 (and knob 38) will indicate, even at a distance, the approximate score so that, by observing the relative position of the pointer, a player can tell, even from his position away from the target device, how he is faring.

The teeth 54, see Fig. 5, of the annular slide 50 may be utilized for striking a gong or other sound-making means; since slide 50 turns for extents depending upon the point value of the particular target area hit, a corresponding number of teeth will actuate the gong, so that the number of such strikings will be an audible indication of the target area hit.

I claim:

1. In a device of the class described, in combination, a central disc target member, a plurality of annular target members in concentric relation to the said disc member, the said members being mounted for a limited extent of axial movement, an indicating slide concentrically disposed outside the said target members and spring-urged for turning movement in a predetermined direction, means including an axially movable member for releasing the said spring-urged indicator slide for turning in the said predetermined direction for extents depending upon the radial distance of the respective target members from the center of the disc target member, each of the said target members having an arm extending radially to the said axially movable member and abuttable therewith to axially move the said member upon said axial movement of a target member.

2. In a device of the class described, in combination, a central disc target member, a plurality of annular target members in concentric relation to the said disc member, the said mem-

bers being mounted for a limited extent of axial movement, an indicating slide concentrically disposed outside the said target members and spring-urged for turning movement in a predetermined direction and provided with spaced teeth, an axially movable member mounting a by-pass dog and spring-urged forwardly to present the said by-pass dog in front of a tooth of the said indicator slide to block spring-urged turning thereof in the said predetermined direction, the said by-pass dog permitting manual turning of the indicator slide in the opposite direction, each of the said target members having an arm extending radially to the said axially movable ring abuttable therewith to axially move the said member to withdraw its said by-pass dog from said blocking relation to the teeth of the indicating slide, the said axially movable member returning the target members to their normal forward position.

3. In a device of the class described, in combination, a central disc target member, a plurality of annular target members in concentric relation to the said disc member, the said members being mounted for a limited extent of axial movement and for rotative movement for angular magnitudes depending upon the radial distance of the respective members from the center of the disc target member, and an indicating slide concentrically disposed outside the said target members and actuated by the said axial movement of the target members for turning extents depending upon the said angular magnitudes of rotative movement of the respective target members.

4. In a device of the class described, in combination, a central disc target member, a plurality of annular target members in concentric relation to the said disc member, the said members being mounted for a limited extent of axial movement and for rotative movement for angular magnitudes depending upon the radial distance of the respective members from the center of the disc target member, and an indicating slide concentrically disposed outside the said target members and spring-urged for turning in a predetermined direction but normally held against turning, each of the said target members having an arm extending radially to the said indicating slide, the distal end of the radial arm of an axially moved target member being adapted to engage the said indicating slide and releasing it for turning in the said predetermined direction, the said released slide turning for an extent depending upon the said angular magnitude of rotative movement of the said axially moved target member.

5. In a device of the class described, in combination, a central disc target member, a plurality of annular target members concentrically disposed relative to the said central disc target member, an annular front surface, said target members having predetermined point values and mounted for a limited extent of axial movement, the said front surface bearing on arithmetic series of numbers totalizing the point values of the respective target members arranged arcuately about the said target members, a pointer movable in an arcuate path around the said series of totalizing numbers, and means actuated by the said axial movement of the target members for turning the said pointer angular extents depending upon the point value of the respective target members.

6. In a device of the class described, in combination, a central disc target member, a plurality of annular target members concentrically disposed relative to the said central disc target

member, a front plate, said target members having predetermined point values and mounted in the said front plate for a limited extent of axial movement, a window in the said front plate, an annular slide rotatively mounted behind the front plate bearing an arithmetic series of numbers totalizing the point values of the respective target members, and means actuated by the said axial movement of the target members for turning the said annular slide angular extents depending upon the point value of the respective target members to bring the number representing the total point value of axially moved target members at the said window.

15. 7. In a device of the class described, in combination, a central disc target member, a plurality of annular target members concentric to the said central disc target member, said target members being mounted for axial and rotative movement, an indicating slide rotatively mounted concentrically of the said target members, means actuated by the said axial movement of the target members for turning the said slide angular extents depending upon the respective target members, and means actuated by the said rotative movement of the target members for indicating the particular target member axially moved.

3. In a device of the class described, in combination, a central disc target member, a plurality of annular target members in concentric relation to the said disc member, the said members being mounted for a limited extent of axial movement and for rotative movement for angular magnitudes depending upon the radial distance of the respective members from the center of the disc target member, and an indicating slide concentrically disposed outside the said target members actuated by the said axial movement of the target members for turning extents depending upon the said limited turning of the respective target members, each of the said target members having an indicating band, means maintaining the said target members turned to a normal position with the said indicating bands of the respective target members aligned, said turning of an axially moved target member causing its said indicating band to move out of alignment with the aligned bands of the other target members to visually indicate which target member had been axially moved.

50. 9. In a device of the class described, in combination, a central disc target member, a plurality of annular target members arranged concentrically thereto, the said target members having predetermined point values and a limited extent of axial and turning movements, an indicating slide turnably mounted concentrically of the said target members, and means actuated by axial movement of the target members for turning the said slide extents depending upon the point value of the respective target members and for turning the said axially moved target member.

10. In a target device for missiles having a predetermined approach thickness, in combination, a central disc target member, a plurality of annular target members disposed concentrically to the said central disc target member, adjacent target members being spaced by an annular clearance wider than the said predetermined approach thickness of the missiles, so that the missiles will not be stuck between adjacent target members, the said target members having predetermined point values and mounted for a limited extent of axial movement, an indicator slide disposed concentrically to the said target members and actuated by the said axial movement thereof for turn-

ing an extent depending upon the respective target members, one of two adjacent target members having an annular flange at the said annular clearance between the two target members overlapping the marginal peripheral portion of the outer target member, whereby a missile missing the said outer target member will strike the annular flange of the first said target member causing axial movement thereof to turn the said indicating scale an extent depending upon the point value of the said axially moved target member.

11. In a device of the class described, in combination, a front plate dished to form a recess and a peripheral flange, a disc target member disposed centrally in the said recess, a plurality of annular target members disposed in the recess concentrically of the said central disc target, the said target members being mounted in the front plate for a limited extent of axial movement, a housing having a rear plate and a front rim aligned with the said peripheral flange to present a flush front surface and spaced from the peripheral flange to provide an annular slot, an annular slide disposed in the said housing behind the marginal portions of the peripheral flange and of the front rim, and a knob at the front of the device secured to the said annular slide and clearing in the said annular slot for manually turning the said annular slide.

12. In a device of the class described, in combination, a circular front plate, a housing having a rear plate and a front rim aligned with the said front plate to present a flush front surface and spaced therefrom to provide an annular slot, an annular slide disposed in the said housing behind the marginal portions of the said front plate and the said front rim, a knob at the front of the device secured to the said annular slide and clearing in the said annular slot for manually turning the said annular slide, an annular flange secured to the inside of the front plate having an annular groove for the inner marginal portion of the annular slide, the said rim of the housing being formed to provide an annular groove for the outer marginal portion of the annular slide.

13. In a device of the class described, in combination, a plurality of concentrically disposed target members mounted for a limited extent of axial movement, the respective target members being turnable for different extents in a predetermined direction from normal rest positions, a slide mounted for turning concentrically of the said target members and spring urged to turn in the said predetermined direction but normally held against turning, means actuated by the said axial movement of the target members for releasing the said slide for turning together with the axially moved target member in the said predetermined direction an extent depending upon the said axially moved target member, and means secured to the said target members to return the said axially moved and turned target member in the direction opposite to the said predetermined direction, to its said normal rest position.

14. In a device of the class described, in combination, a plurality of concentrically disposed target members mounted for a limited extent of axial movement, the respective target members being turnable for different angular extents, a slide provided with spaced teeth and spring urged to turn in a predetermined direction, an axially movable member provided with a by-pass dog and spring-urged forwardly to normally maintain its by-pass dog in holding relation to the

teeth of the slide to prevent turning thereof, each of the said target members having an arm extending radially to the said slide and the said axially movable member, the said radial arm of

5 an axially moved target member pressing the said ring rearwardly to withdraw its said by-pass dog from holding relation to the teeth of the slide and positioning its distal end in engaging relation therewith, and means for maintaining the 10 said radial arm in said relation to retain the by-pass dog withdrawn from, and the distal end of the radial arm engaged with, the teeth of the slide until the said axially moved target member has been turned its said angular extent.

15. In a device of the class described, in combination, a plurality of concentrically disposed target members mounted for a limited extent of axial movement, a slide provided with spaced teeth and spring urged to turn in a predetermined direction, an axially movable member provided with a by-pass dog and spring-urged forwardly to normally maintain its by-pass dog in holding relation to the teeth of the slide to prevent turning thereof, each of the said target

20 members having an arm extending radially to the said slide and the said axially movable member and turnable predetermined angular extents in the said predetermined direction from normal repose positions of their said radial arms, the 25 said radial arm of an axially moved target member pressing the said member rearwardly to withdraw its said by-pass dog from holding relation to the teeth of the slide and positioning its distal end in engaging relation therewith, and arcuate

30 members extending in the said predetermined direction from the said normal repose position of the respective radial arms for angular extents depending upon the said predetermined angular extent of turning of the respective target members, for retaining the by-pass dog withdrawn from, and the distal end of the radial arm engaged with, the teeth of the slide during the predetermined turning of the said axially moved target member.

45 16. In a target for missiles, in combination, a base member, a disc target centrally disposed on the said base member, a plurality of annular targets on the said base member arranged concentrically to the said central disc target, and a member having a bottom and sides hingedly secured at the lower portion of the said base member, the said members being adapted to be turned toward one another with the said base member abutting the edges of said sides of the other 50 member to form a closed carrying case, and adapted to be turned to position the base member normally to the said other member, the said other member serving as a receptacle to catch missiles rebounding from the said base member.

55 17. In a device of the class described, in combination, a central disc target member, a plurality of annular target members concentrically disposed relative to the said central disc target member, the said target members having spaced arcuate flanges, a plate provided with arcuate

60 slots disposed at radial distances from the center of the said plate to receive the said arcuate flanges of the target members, the said plate having arcuate flanges along the arcuate edges of its said arcuate slots to provide sufficient bearing surface for the respective target members to be axially shifted without tilting relatively to the said plate.

65 18. In a device of the class described, in combination, a central disc target member, a plu-

19

rality of annular target members concentrically disposed relative to the said central disc target member, the said target members having spaced arcuate flanges, a plate provided with arcuate slots disposed at radial distances from the center of the said plate to receive the said arcuate flanges of the target members, the said arcuate flanges of the respective target members subtending a smaller angle than the said arcuate

20

slots of the plate receiving the respective arcuate flanges of the target members, whereby the said target members have predetermined angular extents of turning in the said arcuate slots of the plate, the said plate having arcuate flanges along the arcuate edges of its said arcuate slots to provide bearing surfaces for the axial and turning movements of the target members.

LEON H. AMDUR.
